DRAFT ELIMINATOR

Charles Greif Raible, Shaker Heights, Ohio, assignor, by mesne assignments, to The Sentry Stop-A-Draft Co., Cleveland, Ohio, a corporation of Ohio

Application March 18, 1938, Serial No. 196,754
Renewed July 10, 1939

7 Claims. (Cl. 20—68)

This invention relates to sealing devices or draft eliminators of the type adapted to be mounted on a door, or the like, and to be operated automatically during opening and closing movements of the door.

An object of my invention is to provide an improved device of this kind embodying novel features and characteristics contributing to the economical manufacture thereof and to the efficient and reliable functioning of the device during use.

Another object of my invention is to provide an improved draft eliminator, of the type referred to, having novel actuating means for the sealing member whereby one end of the sealing member is actuated in advance of its other end.

A further object of my invention is to provide an automatic door sealing device of the type having spaced levers or cams for actuating an elongated sealing member and in which such levers or cams are of dissimilar shape whereby one end of the sealing member is actuated in advance of its other end to avoid interference with a floor covering adjacent the door opening.

Still another object of my invention is to provide an improved construction for an automatic door sealing device whereby relatively inexpensive sheet metal can be used for most of the parts and the cost of the manufacture of the device thereby greatly reduced as compared with prior devices embodying parts formed as castings or forgings.

Yet another object of my invention is to provide an improved draft eliminator in which tension springs extending in diverging relation are connected with the sealing member for retracting and centering the same in the casing.

My invention may be further briefly summarized as consisting in certain novel combinations and arrangements of parts hereinafter described and more particularly set out in the appended claims.

In the accompanying sheets of drawings:

Fig. 1 is an elevational view showing a door having my improved draft eliminator mounted thereon;

Fig. 2 is a longitudinal sectional view taken through the draft eliminator and the adjacent portion of the door;

Fig. 3 is a similar longitudinal sectional view but showing the sealing member projected from the casing of the device;

Fig. 4 is a partial edge view of a door having my draft eliminator mounted thereon;

Fig. 5 is a transverse sectional view taken

through the lower edge of the door and through my draft eliminator mounted thereon, as indicated by line 5—5 of Fig. 2;

Fig. 6 is a partial transverse sectional view taken through the device and door as indicated by line 6—6 of Fig. 3;

Fig. 7 is an elevational view with parts broken away illustrating the functioning of the dissimilar cams of my improved draft eliminator;

Fig. 8 is an elevational view showing a door 10 having another form of my draft eliminator mounted thereon;

Fig. 9 is a longitudinal sectional view taken through such modified form of my draft eliminator;

Fig. 10 is a similar longitudinal sectional view but showing the sealing member projected from the casing;

Fig. 11 is a partial transverse sectional view taken through the device as indicated by line 11—11 of Fig. 9;

Fig. 12 is another partial transverse sectional view taken as indicated by line 12—12 of Fig. 9; and

Fig. 13 is a developed plan view showing the sheet metal blank from which the casing of the device may be formed.

More detailed reference will now be made to the accompanying drawings in which I have shown what I regard to be preferred forms of my improved sealing device, but it will be understood, of course, that the invention may be embodied in various other similar devices and improvement features thereof.

In the form of my draft eliminator illustrated in Figs. 1 and 2, I show a door casing 15 having a door 16 hinged thereto and provided with a longitudinal slot or recess 17 in its lower end in which my improved draft eliminator 18 is mounted. As will appear more fully from the following description, my draft eliminator is of the automatic type, that is, has an elongated sealing member which is retracted during opening movement of the door and is projected in response to closing movement of the door.

The draft eliminator 18 comprises an elongated hollow sheet metal casing 20, of a shape and size to be inserted into a slot 17 provided in the lower end of the door 16, and a sealing member 21 movable in the casing and adapted to be projected therefrom automatically during closing movement of the door. The casing 20 may be made from a metal sheet bent or formed to substantially U-shape, as shown in Fig. 5, whereby a longitudinal slot or opening 22 is provided along 50

the lower edge of the casing through which the sealing member 21 is adapted to be projected. The casing is preferably left open at its ends when the device is to be mounted interiorly of the 5 door, as shown in Fig. 1, and may have transverse pins or studs 23 connected with the side walls of the casing adjacent such open ends. These transverse studs serve to brace the side walls of the casing and cooperate with members 25 and 26

10 by which the device is mounted on the door.

The members 25 and 26 may comprise plates mounted on the edges of the door by means of screws 27 so as to form closures for the ends of the recess 17 and may have inwardly projecting 15 means, such as the brackets 28 and 29, which extend into the open ends of the casing and engage under the transverse studs 23 for supporting the casing in the recess. The bracket portions of members 25 and 26 may be formed integral with 20 the plates or may be separately formed and riveted or welded thereto. The bracket portion of one of the closure and mounting members, preferably the bracket 29 of the member 26, has a hook-like portion 30 which cooperates with the stud 23 to prevent longitudinal shifting of the casing 29 in the door recess. Shifting of the casing in the recess in the opposite direction may be prevented by the engagement of the adjacent end 25 of the casing with the plate of the member 26.

30 The sealing member 21 may comprise an elongated strip 32 formed of felt, sponge rubber, or any suitable flexible packing material, and an elongated holder 33 for such strip. I construct the holder 33 as a sheet metal member having a 35 cross-sectional shape to provide a longitudinal channel recess in which the packing strip 32 engages and is suitably held as by having portions of the side walls of this channel-shaped member deflected inwardly to pinch or grip the packing 40 strip as indicated at 34. The packing strip 32 is preferably made longer than the holder 33 so that at one end of the device, such as at the end adjacent the supporting and closure member 25, an end portion 35 of the strip extends beyond 45 the adjacent end of the holder. This extra length for the packing strip is desirable because if the adjacent edge of the door 16 should need to be planed off, either at the time the draft eliminator is mounted on the door or at some subsequent time, more or less of the projecting portion 50 35 can be cut off before the member 25 is mounted or replaced on the edge of the door. The strip will then be of proper length for the door and will produce a seal of maximum length without 55 undue pressure or scraping of the end of the strip against the member 25.

For actuating the sealing member 21 I provide a pair of pivoted levers or cams 37 and 38 which act on the sealing member to project the same, 60 and a pair of tension springs 39 which are connected with the sealing member and serve to retract the same and hold it against the levers. For imparting motion to the levers I provide an elongated actuating member or bar 40 which is 65 movable longitudinally in the casing and has a finger or pin 41 at one end thereof which projects from an edge of the door to cooperate with the door casing, or a striker 42 mounted thereon, during opening and closing movements of the 70 door. The levers 37 and 38 are mounted respectively on the pivots 43 and 44 which extend transversely of the casing. These pivots are preferably in a form of hollow rivets which extend 75 through the side walls of the casing and serve to connect and strengthen the walls of the cas-

ing as well as to provide for the pivotal mounting of the levers. The levers may be stamped from sheet metal and preferably have bushings 45 mounted therein, as by means of a press fit or otherwise, such bushings being longer than the 5 thickness of the levers and serving for journaling the levers on the hollow rivets. By making the bushings 45 longer than the levers they will also tend to hold or centralize the levers substantially midway between the walls of the casing. 10

As shown in Fig. 2, the levers 37 and 38 may have upwardly extending arms 46 and 47 which are pivotally connected with the actuating bar 40 at longitudinally spaced points as by means of transverse pivot pins 48. The levers also have 15 angularly extending arms 49 and 50 which engage the sealing member 21 and exert a camming action thereon. The tension springs 39 may have their ends connected with the actuating bar 40 and the holder 33 of the sealing member 20 so as to normally act on the latter to hold the same against the arms 49 and 50 of the levers. Because of their diverging relation the springs tend to centralize the sealing member longitudinally of the casing. 25

I purposely form the holder 33 of the sealing member 21 with a longitudinal groove in the top or inner edge thereof in which the arms 49 and 50 of the levers 37 and 38 engage. When the holder 33 is of sheet metal, this groove may be 30 formed in the holder by constructing the latter with the transverse web portion 52 thereof deflected inwardly, as shown in Fig. 5. By providing this member with such a longitudinal groove I secure interengagement between the 35 levers and the sealing member whereby the levers are always retained in proper camming engagement with the sealing member and are not likely to be disengaged therefrom as might otherwise result from jarring or slamming of the door. 40

The actuating bar 40 is also preferably of sheet metal construction and may be in the form of an elongated channel-like member formed from sheet metal bent to the cross-sectional shape shown in Fig. 5. By forming this bar from sheet 45 metal, an advantage as to cost and weight is realized and, at the same time, I obtain a longitudinal recess 53 into which the arms 46 and 47 of the levers 37 and 38 may extend between the offset longitudinal flange portions 54. The 50 actuating bar 40 is supported in the casing substantially entirely by the arms 46 and 47 of the levers. By constructing this bar as a hollow sheet metal part it will be seen that the pivotal connections with the levers can be more easily made and the actuating bar will always be retained in proper position by the levers with its longitudinal midplane coinciding substantially with that of the levers and of the sealing member 21. The 55 hollow construction for the actuating bar 40 also permits the pin or finger 41, which may be of solid metal, to be readily mounted in an end of the bar.

Difficulty has been experienced heretofore in the operation of automatic draft eliminators, of 60 the type here under consideration, by reason of the sealing member engaging or scraping against a rug or other floor covering extending near the door opening. I have overcome this difficulty by providing for actuation of the sealing member 65 21 in such manner that one end of this member, preferably the end thereof nearest the free edge of the door, will be actuated in advance of the other end so that by the time the free edge of the door swings to a position over the rug or 70 75

carpet 55 this end of the sealing member will have been lifted sufficiently to clear the floor covering. I obtain this desired result by constructing the levers or cams 37 and 38, or at least the arms 49 and 50 thereof, of dissimilar shape so that one of the levers, for example the lever 38, will act as a "fast" lever or cam as compared to the other or "slow" lever or cam.

As shown in Figs. 2 and 3 the arm 49 of the lever 37 may be of bowed or arcuate form so that its initial point of contact with the sealing member 21 is at an intermediate point 56 which is at a relatively short lever-arm distance from the pivot 43. On the other hand the arm 50 of the lever 38 is made substantially straight so that its initial point of contact 57 with the sealing member 21 will be at or adjacent a corner or outer end, or in other words, at a relatively long lever-arm distance from the pivot 44. With this shape for the arm or cam portions 49 and 50 of the levers 37 and 38 it will be observed that when the actuating bar 40 is moved toward the right, as will result from engagement of the pin 41 with the striker 42 when the door approaches its closed position, the lever 38 will cause the right-hand end of the sealing member 21 to be projected in advance of its other end. When the door starts its opening movement the "fast" lever 38 will permit the right-hand end of the sealing member 21 to be lifted more quickly than its other end, as illustrated in Fig. 7, so that this end of the sealing member will readily clear the floor covering 55.

In Figs. 8, 9 and 10 I have shown a modified form of my draft eliminator which can be used when it is more convenient to mount the device on the face of the door instead of in a longitudinal recess formed in the door. In Fig. 8 I show a door frame 60 and a hinged door 61 having a draft eliminator 62 of the last mentioned form mounted thereon. When the draft eliminator is to be mounted on an outer face of the door, as in this arrangement, it is preferable to have the pin 63 of the actuating bar project from the device on the knob side of the door for engagement with the striker 64.

As shown in Figs. 9 and 11 the draft eliminator 62 may comprise a hollow sheet metal casing 65 and a sealing member 66 movable therein and adapted to be projected through the longitudinal slot-like opening 67 at the lower edge of the casing. The casing 65 preferably has end walls 68 and 69 which close the casing at its ends except for an opening 70 in the wall 69 through which the pin 63 projects. The casing may be formed from a sheet metal blank 71 having substantially the form or outline shown in Fig. 13. The blank may be bent substantially along the longitudinal lines 72 that the section 73 of the blank included between such lines forms the top edge of the casing and the oppositely extending portions 74 and 75 form the side walls of the casing. The projections 76 and 77 may be deflected into overlapping relation during the shaping of the casing to form the end walls 68 and 69 thereof.

The sealing member 66 may comprise an elongated strip 78 of felt or other suitable packing material, which is gripped and held by the elongated channel-shaped holder 79. The holder 79 is preferably formed of sheet metal and has a longitudinal groove 80 in its upper edge in which the longitudinally spaced cams or levers 81 and 82 engage.

The actuating levers 81 and 82 are mounted in the casing by providing the latter with trans-

verse hollow rivets 83 which connect the side walls of the casing as well as to form pivots for these levers. The levers preferably have tubular bushings 84 pressed thereinto, or otherwise mounted therein, and which are journaled on the hollow rivets. The levers may be stamped from sheet metal and may comprise arms 81a and 82a and angularly extending arms or cams 81b and 82b.

An elongated actuating bar 85 is connected with the arms 81a and 82a of the levers by means of transverse pivot pins 87. This actuating bar is preferably of channel-like sheet metal construction so that the arms of the levers 81 and 82 may extend thereinto.

The sealing member 66 is normally held against the arms or cams 81b and 82b of the levers 81 and 82 by means of the divergently extending tension springs 88 which have their ends connected respectively with the sealing member and the actuating bar 85.

The actuating levers 81 and 82 are shown in this instance as being of similar or identical shape, but it should be understood that one or the other of these levers may be of dissimilar shape as in the form of the invention shown in Fig. 2, if it should be desirable to cause one end of the sealing member to be actuated in advance of the other.

In addition to the hollow rivets 83 which form pivots for the levers 81 and 82, I may provide hollow studs or rivets 91 adjacent the ends of the casing for connecting the side walls thereof. Spacers 89, similar in form to the bushings 84 of the levers, are preferably provided on these hollow rivets to prevent the side walls of the casing from being pinched or unduly deflected inwardly during the riveting. When the device is mounted on the door 61, as shown in Fig. 8, the hollow rivets 83 and 91 provide convenient openings for suitable attaching screws 90.

From the foregoing description and the accompanying drawings it will now be readily seen that I have provided a simplified construction for draft eliminators whereby these devices can be manufactured more economically and are adapted to function more satisfactorily during use. It will be seen that these ends are attained, in part, by the use of sheet metal parts of novel form in the manufacture of the device and, in part, from the use of a novel form and arrangement for the actuating cams or levers and the retracting springs. It will be seen, furthermore, that I have provided novel means for mounting the device on the door and have provided for adjustment or fitting of the packing strip whereby a maximum length of seal along the lower edge of the door is obtained.

While I have illustrated and described the draft eliminators of my invention in a somewhat detailed manner, it will be understood, of course, that I do not wish to be limited to the precise details of construction and arrangements of parts herein disclosed, but regard my invention as including such changes and modifications as do not constitute a departure from the spirit of the invention and the scope of the appended claims.

Having thus described my invention, I claim:

1. In a door sealing device of the type adapted to be mounted on a door and having an elongated sealing member to be projected and retracted during closing and opening movements of the door, means for actuating the sealing member so as to cause one end thereof to be actuated in advance of the other end comprising a pair of

- spaced actuators cooperating with the sealing member, the member cooperating portion of one actuator being of a different shape than the corresponding portion of the other actuator.
5. 2. In a sealing device of the character described, the combination of an elongated hollow casing having a longitudinal opening, an elongated sealing member movable in said casing and adapted to be projected through said opening, and means for actuating said sealing member so as to cause one end thereof to be actuated in advance of the other comprising a pair of longitudinally spaced cams one of which has a shape substantially different from the other.
10. 3. In combination, a door having a longitudinal recess in the lower end thereof, an elongated sealing device disposed in said recess comprising an open-ended hollow casing having pins extending transversely thereof at points spaced inwardly from its ends, and plates mounted on the edges of the door to close the ends of said recess and having arms extending into the open ends of said casing and engaging under said transverse pins for supporting the sealing device in said recess.
15. 4. In combination, a door having a longitudinal recess in the lower end thereof, an elongated sealing device disposed in said recess comprising an open-ended hollow sheet metal casing having members extending transversely thereof adjacent its ends, and plates mounted on the edges of the door to close the ends of said recess and having means extending into the open ends of said casing and engaging said members for supporting the sealing device in said recess, the member engaging means of one of said plates being of hook-like form and adapted to prevent longitudinal shifting of the casing in the recess.
20. 5. In a sealing device of the character described, an elongated hollow casing having an opening along an edge thereof, an elongated sealing member movable in said casing and adapted to be projected through said opening, an elongated bar longitudinally movable in said casing, and levers between the bar and sealing member for projecting the latter in response to longitudinal movement of the bar, said bar being formed
- of sheet metal and having an offset longitudinal hollow portion of box-like cross-sectional shape with a pair of spaced longitudinal flanges projecting therefrom and defining a slot opening into said hollow portion and said levers extending into said hollow portion through said slot and having centralizing cooperation with said flanges.
6. In a sealing device of the character described, an elongated casing having spaced side walls and a longitudinal opening, an elongated sealing member movable in the casing and adapted to be projected therefrom through such opening, an elongated actuating bar movable longitudinally in the casing, a pivot extending transversely of the casing, a lever for transmitting motion between said bar and sealing member and having an opening therein, and a bushing secured in the opening of the lever and serving to mount said lever on said pivot, said bushing being substantially longer than the thickness of said lever and its ends cooperating with said casing walls for locating the lever therebetween.
7. In a sealing device of the character described, an elongated hollow casing having spaced side walls and a longitudinal opening, an elongated sealing member movable in said casing and adapted to be projected through said opening, an elongated actuating bar movable longitudinally in said casing, a pivot extending transversely of the casing, a lever for transmitting motion between said bar and sealing member and having an opening therein, and a bushing secured in the opening of the lever and serving to mount the same on said pivot, said bushing being substantially longer than the thickness of said lever and its ends cooperating with said casing walls for locating the lever therebetween, said actuating bar being formed of sheet metal and having a longitudinal hollow portion of box-like cross-sectional shape with a pair of spaced offset longitudinal flanges projecting therefrom and defining a slot opening into said hollow portion and said lever extending into said hollow portion through said slot and having centralizing cooperation with said flanges.
- CHARLES GREIF RAIBLE.
